VAPOR PHASE OPERATION

Eugene J. Houdry, Haverford, Pa., assignor to
 Houdry Process Corporation, Wilmington, Del.,
 a corporation of Delaware

Application July 10, 1937, Serial No. 152,879

10 Claims. (Cl. 196—8)

This invention relates to the division of a composite vapor stream into higher and lower boiling parts without fractionation effected by cooling or by partial condensation of the stream. While having features of general application, it is of particular importance in the transformation or conversion of higher boiling hydrocarbons into lower boiling hydrocarbons in the production of motor fuels, especially those in the gasoline boiling range. The material to be converted may be from any known or suitable source such as petroleum, shale oil, bitumens, coal, lignite, and distillates, residues and derivates thereof. In the production of motor fuels such as gasoline from higher boiling hydrocarbons only partial conversion is possible in a single operation under the best operating conditions. To carry the reaction further simply means that some of the desired products are lost due to secondary reactions which further convert the gasoline into gas and coke. Hence to obtain from a given charging stock a maximum yield of lower boiling hydrocarbons it has been customary to separate out the light hydrocarbons already produced and then to carry the conversion further on the higher boiling material. The separation has been effected by a partial condensation of the products from the transforming operation to separate out in liquid form the higher boiling material which is then revaporized and subjected to further transformation either by itself or by recycling it through the initial operation with fresh charging material. One object of the invention is to effect a separation of the lighter and the heavier components of a composite vaporous or gaseous stream without condensation. Another object is to maintain hydrocarbons undergoing conversion continuously in vapor phase until conversion to the desired extent has been effected. Another object is to avoid condensation of material suitable for conversion until conversion is completed. Other objects will be apparent from the detailed discussion which follows.

Heretofore it has been known to separate the vapors of benzene, gasoline and similar light hydrocarbons from fixed gases, natural gas, etc., by various "so-called" absorption systems utilizing liquid or solid absorbents. The absorption is effected at low or atmospheric temperatures and the absorbed material is subsequently ejected from the absorptive medium by a distilling operation effected by the application of heat or by the use of steam or hot gases. I have now discovered how to treat a composite stream of hydrocarbons of wide boiling range so that relatively high boiling hydrocarbons such as heavy naphtha, kerosene, gas oil, fuel oil, etc. can be separated from lower boiling hydrocarbons in

the gasoline boiling range and above by a somewhat similar operation and at temperatures where all components are in vapor phase. The separation is not clear cut but is sufficiently close to permit its use with important advantages in the conversion of hydrocarbons.

The separation is effected by the use of porous contact material in the form of bits, fragments or molded pieces having little or no catalytic activity but a preferential absorption for higher boiling hydrocarbons. The mass is maintained at a temperature above that required to keep the stream in vapor phase and may correspond to that of the transforming operation as, for example from 750 to 950° F. Contact of hydrocarbons with the mass is restricted to a very short period (not in excess of a few seconds) whereupon they are promptly ejected by an extraneous medium at high temperature such as superheated steam. The ejected higher boiling hydrocarbons are thus not only in vapor phase but may also be at a proper temperature for further conversion.

In order to illustrate the invention and the manner of its use concrete embodiments thereof are shown in the accompanying drawing in which:

Fig. 1 is a diagrammatic view showing an application of the invention to the thermal conversion of hydrocarbons; and

Fig. 2 is a diagrammatic view showing an application of the invention to the catalytic transformation of hydrocarbons.

In the high temperature division of a vapor stream into low boiling and high boiling parts, a battery of separators, two or more in number, is utilized in order that the operation may go on continuously. In Fig. 1, three such separators, indicated by reference character 3, are shown arranged in a battery having individual valved connections at one end to vapor supply line 4, to a line 5 for an ejecting medium, and to a line 6 for fumes. At their opposite ends, separators 3 have individual valved connections to a line 7 for removing the low boiling part of the vapors, to a line 8 for removing the high boiling part of the vapors, and to a line 9 for supplying regenerating medium. The separators contain highly porous material having little or no catalytic activity under the operating conditions, but manifesting a preferential absorption for the high boiling parts of a vapor stream. This porous material is preferably silicious in character and arranged in the form of bits, fragments, or molded pieces which permit reasonably free movement therein of gaseous materials charged thereto and which enable the contact material to be regenerated in place. The contact material may be composed of natural or synthetic material, such, for example, as molded pieces of silicious or porcelaneous material, silica gel, blends of

silica and alumina in gel or other form, etc. If the contact material has catalytic activity, this may be reduced as desired, in known ways, as by prolonged heat treatment at suitably high temperature.

Separators 3, within which the porous material is disposed, may be of any suitable or desired type. For example, they may have the mass disposed therein in a deep bed with the 10 charge passing therethrough from end to end, or various arrangements may be made for distributing the charged fluids within the mass of contact material or for effecting localized movement of the fluids within the mass, as 15 closed, for example, in my U. S. Patent No. 2,042,468, issued June 2, 1936, or in the U. S. Patent of A. Joseph, No. 2,042,469, issued on the same date. Heat may be supplied to the mass through the walls of the case or by heating 20 members embedded in the mass, as may be desired.

The vapor separators operate efficiently in a temperature range of 750° to 950° F., and this is a range in which many transforming reactions 25 are effected on organic materials, including hydrocarbons. The operation involves a short cycle, i. e., the vapor stream, which is to be divided into lower and higher boiling parts, is sent into one of the separator cases 3 from supply line 4 30 for a few seconds, as up to 10 seconds, the porous material within the case holding back or retaining the higher boiling parts while the lower boiling parts pass through the separator into vent line 7. The stream of vapors from line 4 is then shut off from this separator and sent to another, while the outlet to line 7 is closed. Thereupon, the 35 ejecting medium, such as hot gases or superheated steam, is sent by line 5 into the separator for a few seconds (the same number of seconds or a 40 greater number), whereupon the higher boiling vapors retained in the mass are ejected and pass out through the valved connection to outlet line 8. The feeding of the vapor stream from line 4 to the separator may then be resumed and the 45 steps repeated. After a time, the porous mass in the separators loses its ability to retain the higher boiling vapors, due to an accumulation of gummy material in the mass, whereupon purification or regeneration of the mass is necessary. This is 50 effected by sending a regenerating medium from line 9 into the cases, which medium may be a liquid or gaseous solvent to wash out the impurities, which escape by line 6, or the regeneration may be effected by an oxidizing medium, such 55 as air, which burns out the gummy material in the mass, the fumes escaping by line 6.

The composite stream of vapors passing to line 4 may come from any known or suitable source. For example, they may result from the transformation or conversion of lower boiling hydrocarbons into higher boiling hydrocarbons. If the conversion is effected entirely by thermal means, as by heat or heat and pressure, a tar separator, such as 10 will be interposed between 60 the converting means and the vapor separators, inasmuch as thermal operations produce tar and this tarry material would interfere with and stop the action of the contact material in separators 3. The converting means may be of any known 65 or suitable type, such, for example, as tube and tank, de Flores, Cross, Dubbs, etc. By way of illustration, a still 11 only is shown, but it is to be understood that a reaction chamber, flash vaporizer, or other apparatus, may be used in addition to the still and/or tar separator.

The separator high boiling vapors leaving separators 3 by line 8 may pass to another still or converting apparatus such as 11, as by branched line 12, or some or all of these vapors may be sent by line 13 to be recycled with the fresh 5 charge passing to still 11. They may be mixed with the fresh charge before it enters the still, as indicated, or sent into an intermediate coil, or through a separate coil in the same still, as may be desired. The ejecting medium supplied 10 by line 5 will be at a pressure sufficiently high to send the vapors of the high boiling part into the supply line to still 11. For example, if steam (superheated or otherwise) is used as the ejecting agent, it may be supplied at a slightly greater 15 pressure than is utilized in still 11, as, for example, 5 pounds additional pressure. If a reaction chamber follows still 11, line 13 may join the line between the still and the reaction chamber 20 and deliver the separated high boiling material 20 at proper temperature and pressure for further conversion with the fresh charge coming from still 11.

Fig. 2 shows one arrangement for utilizing the invention in connection with catalytic cracking 25 operations. The figure is not only diagrammatic but also in order to make it as simple as possible only one piece of apparatus has been indicated in each zone. Hence it must be understood that for continuous operation of the system there will be two or more catalyzers in each cracking zone and one or more batteries of vapor separators. In the form shown, the fresh charge is passed into heater 11a, where the charged material is vaporized and raised to a suitable temperature which is usually not in excess of 900° F. The vaporized material goes into the first pass catalytic cracker 20, whence the cracked products pass through line 4 to vapor separator 3a, whence the low boiling part will be discharged 40 through line 7a to storage or to further treatment, as in fractionator 21, from which the gasoline and gas will pass overhead through line 22, while a heavier fraction in the gas oil boiling range will be removed from the bottom of the 45 fractionator through line 23. During the intermittent shut-off periods for separator 3a, the high boiling part of the vapors will be ejected by an ejecting medium such as superheated steam admitted through line 5a, the ejected higher boiling part passing by line 8a for further treatment. While this higher boiling product could be recycled, after the manner indicated in Fig. 1, it is preferable to send it through a second pass 50 cracker such as 24, operating at the same or a somewhat higher temperature than the first pass catalytic cracker 20, the cracked products from 24 passing from the latter by line 4b for another vapor separating operation. This second separating operation could be effected in another vapor separator or series of vapor separators, but, inasmuch as the arrangement in Fig. 2 provides for recycling the high boiling part through the second pass catalytic cracker, these products are sent into vapor separator 3a, so that all higher 55 boiling parts separated from the products of both catalytic crackers 20 and 24 are continuously sent into and through the second pass cracking zone. This permits the charged material to be cracked to virtual exhaustion. The catalytic 60 crackers 20 and 24 may correspond to any of the forms shown in the aforesaid Houdry and Joseph patents, and the catalytic masses contained therein are preferably active blends of silica and alumina of natural or artificial origin, with or 65 70 75

without the addition of other metallic compounds, including manganese, such as disclosed, for example, in my U. S. Patents Nos. 2,078,945, and 2,078,951, both issued on May 4, 1937. In other words, the contact material in the catalytic cracking zones has a high degree of catalytic activity as compared with the very low or negligible activity of the porous mass utilized in the vapor separators 3 and 3a. For a two-stage operation, such as disclosed in Fig. 2, a good temperature for the first pass cracker 20 is of the order of 825° to 850° F., while the temperature of the catalytic mass in the second pass catalytic cracker 24 is generally slightly higher, as of the order of 850° to 875° F. The vapor separator 3a is preferably operated at a temperature which is suitable for the second pass cracking operation such as 850° to 875° F. If necessary, additional heat to bring the high boiling part of the separated vapors, passing through line 9a to the second pass cracker 24, to reaction temperature may be supplied by the ejecting medium admitted through line 5a, which is by preference superheated steam.

Separators 3 and 3a effect a rough but sufficiently close division of the vapors for practical purposes, and very substantially reduce the amount of heat input necessary for further conversion of the higher boiling part of the vapors. For example, let us assume that the composite vapor stream passing to the separators 3 or 3a contains 2% of hydrocarbon gases and 98% normally liquid hydrocarbons in the ratio of 40:58 gallons of low boiling to high boiling hydrocarbons. The vapor stream is sent in a cycle of 2 seconds through vapor separators such as 3 and 3a which thereafter are 4 seconds in the ejecting stage. The separator splits the vapor stream into two parts in the ratio of about 40:60. Some 33 gallons of hydrocarbons in the gasoline boiling range and some 6 gallons of heavier hydrocarbons are in the low boiling part which leaves the separators by lines 7 or 7a. The high boiling part, which leaves the separators by lines 8 or 8a, contains the remainder of the gasoline, which is about 7 gallons, and the rest of the higher boiling hydrocarbons, some 52 gallons. Most of the gasoline in the high boiling part is heavy naphtha, which is susceptible of conversion into light or lower boiling products in the gasoline range, when the operation is thermal, as in Fig. 1, or catalytic, as in Fig. 2, and such proportion of naphtha is not sufficient to adversely affect the second stage cracking operation to any important extent. Any adjustments deemed desirable in the temperature of the vapor streams passing to separators 3 and 3a or of the vapor streams leaving such separators may be effected by conventional heat exchange apparatus (not shown) in lines 4, 7 and 8 of Fig. 1 and in lines 4a, 4b, 7a and 8a of Fig. 2. Such temperature adjustment may also be effected within or by the vapor separators themselves as previously indicated herein.

To secure the best results from the invention, the separator cases should be small and the vapor stream should be sent therethrough at a high rate during the very short periods in which they are "on stream." The limiting factor is the avoidance of cracking in these cases. In general, the separator cases are from $\frac{1}{20}$ to $\frac{1}{10}$ the size of catalytic cases used for the catalytic cracking zones. A good commercial operation is secured when the charging rate to the separator cases (figured as ratio of volume of oil [liquid] per hour

per volume of contact mass) is in the range of 5:1 to 13:1.

The present invention is a solution, long sought, of the problem of keeping hydrocarbon charge continuously in vapor phase until conversion or transformation into low boiling hydrocarbons has been effected to the desired extent without sacrificing in any important degree the light products already made in the operation. As indicated by Fig. 1 the invention has immediate application to and use in existing thermal plants employing internal recycling. Only very minor changes are required which will pay for themselves in a very short time by the resulting economy in the operation of such plants. The preferred manner of using the invention, however, is illustrated in Fig. 2. While the cracking zones designated as "first pass" and "second pass" may operate either thermally or catalytically, catalytic operation in both zones with active blends of silica and alumina as described is preferred in view of the higher yield and better quality of products.

It is to be understood that the embodiments of the invention herein shown and described are for the purpose of illustration only and that the invention covers all changes, variations, modifications and applications within the scope of the appended claims.

I claim as my invention:

1. Process of effecting a rough division of a composite vapor stream into higher and lower boiling parts without fractionation by cooling or partial condensation which comprises sending the vapor stream at elevated temperature for a few seconds into a zone containing porous contact material maintained in the temperature range of 750° to 950° F., said material having little or no catalytic activity at such temperature and for such time of contact but having a preferential absorption for higher boiling components of said vapor stream, shutting off said stream and ejecting the higher boiling components in vapor form from said contact material by a hot gaseous purging medium.

2. Process of effecting a rough division of a composite vapor stream into higher and lower boiling parts without fractionation by cooling or partial condensation which comprises sending the vapor stream for a period not in excess of ten seconds into a zone containing porous contact material maintained in the temperature range of 750 to 950° F., said material having little or no catalytic activity at such temperature and for such time of contact and having the ability to hold back within itself the higher boiling components of said vapor stream while letting the lower boiling components pass, shutting off said stream, ejecting the higher boiling components in vapor phase from said contact material by a hot gaseous purging medium, repeating the aforesaid steps, and from time to time freeing said contact material of accumulated gummy deposits resulting from a series of separating operations on said vapor stream.

3. Process of effecting a rough division of a composite vapor stream into higher and lower boiling parts without fractionation by cooling or partial condensation which comprises sending the vapor stream at elevated temperature for a few seconds into a zone containing porous silicious contact material at a temperature of the order of 850° to 875° F., said material having little or no catalytic activity at such temperature and for such time of contact but having a preferential absorption for higher boiling components of said

vapor stream, shutting off said stream, ejecting the higher boiling components in vapor form from said material by a gaseous purging medium heated to about the aforesaid temperature, stopping the ejecting procedure when said material is substantially purged, again sending said vapor stream into said zone, and repeating the above steps.

4. Continuous process of effecting a rough division of a composite vapor stream into higher and lower boiling parts without fractionation by cooling or partial condensation which comprises disposing in at least two zones porous contact material having a preferential absorption for higher boiling components of said vapor stream, maintaining the contact material in the temperature range of 750° to 950° F., sending the vapor stream at elevated temperature into each of said zones in sequence for a brief interval during which the lower boiling components pass through while the higher boiling components are retained by the porous contact material, ejecting the retained higher boiling components in vapor phase from the contact mass in each zone by a gaseous purging medium while the vapor stream is being sent to another zone, and repeating the sending and ejecting steps so that the separated higher and lower boiling streams of vapors are produced in a substantially continuous manner.

30 5. In the conversion of higher boiling hydrocarbons into lower boiling hydrocarbons the process steps of subjecting a charge of higher boiling hydrocarbons at elevated temperature to a converting operation, and then separating the reaction products with the aid of contact material having a preferential absorption for higher boiling hydrocarbons while such reaction products are maintained at temperatures in excess of 750° F., the separation being effected without substantial loss of heat by contacting such reaction products for a few seconds with said contact material and by promptly ejecting the hydrocarbons retained by said material by means of a gaseous purging medium, at least two bodies of contact material being utilized to conduct the separating step in a continuous manner by shifting the feeding of hydrocarbons from one body of contact material to another and by effecting the ejecting step in the intervals between successive feedings of hydrocarbons.

55 6. In the conversion of higher boiling hydrocarbons into lower boiling hydrocarbons the process steps of subjecting a charge of higher boiling hydrocarbons at elevated temperature to a converting operation to produce lower boiling hydrocarbons, removing tarry and asphaltic material from the products of conversion, dividing the remaining products while in vapor phase and maintained at conversion temperature into a higher boiling part and a lower boiling part by intermittently contacting said remaining products for a few seconds with a porous mass having little or no catalytic activity but a preferential absorption for higher boiling hydrocarbons and by intermittently ejecting the higher boiling hydrocarbons therefrom, and continuing the conversion of said higher boiling part.

7. In the conversion of higher boiling hydrocarbons into lower boiling hydrocarbons the process steps of subjecting a charge of higher boiling hydrocarbons at elevated temperature to a converting operation to produce lower boiling hydrocarbons, sending all the reaction products while in vapor phase into contact with a porous silicious mass which retains the heavier hydrocarbons

while permitting the lighter hydrocarbons to pass thereby effecting a rough separation into lighter and heavier hydrocarbons and without a drop in temperature, ejecting the heavier hydrocarbons from said mass by a hot gaseous medium, 5 and subjecting said ejected heavier hydrocarbons directly to another conversion step.

8. In the production of motor fuel the process steps of sending a charge containing high boiling hydrocarbons under reaction conditions of temperature and pressure into a reaction zone to effect partial conversion thereof into lower boiling hydrocarbons, sending all the vapor phase hydrocarbons from said conversion zone at a temperature of at least 750° F. and in vapor phase into 10 a separating zone containing a porous mass maintained at substantially the temperature of said conversion zone and having a preferential absorption for higher boiling hydrocarbons, ejecting the higher boiling hydrocarbons from said separating zone in vapor phase without cooling the same and at suitable temperature for further conversion, and directly continuing the conversion of said ejected higher boiling hydrocarbons. 20

9. In the production of motor fuel the process steps of sending a charge of high boiling hydrocarbons under reaction conditions of temperature and pressure into a reaction zone to effect partial conversion thereof into lower boiling hydrocarbons, sending the hydrocarbons from said conversion zone at a temperature above 750° F. and in vapor phase intermittently for a few seconds into a separating zone containing a porous mass which retains the heavier hydrocarbons while permitting the lighter hydrocarbons to pass thereby effecting a rough separation into lighter and heavier hydrocarbons, intermittently ejecting the heavier hydrocarbons from said mass in vapor phase and without substantial loss of heat by a hot gaseous medium, and continuing the conversion of said ejected heavier hydrocarbons by sending them at reaction temperature and pressure to join the charge to said reaction or conversion zone. 30

10. In the production of motor fuel the process steps of sending a charge of high boiling hydrocarbons under reaction conditions of temperature and pressure into a primary reaction zone to effect partial conversion thereof into lower boiling hydrocarbons, making a rough separation 50 of the products of the reaction into lower and higher boiling hydrocarbons by sending the hydrocarbons from said primary conversion zone in vapor phase and intermittently for a few seconds into a separating zone containing a porous mass 55 having a preferential absorption for higher boiling hydrocarbons and by intermittently ejecting the higher boiling hydrocarbons from said separating zone in vapor phase and without substantial loss of heat, sending said ejected material 60 under reaction conditions of temperature and pressure into a second reaction zone for effecting partial conversion thereof into lower boiling hydrocarbons, and sending the hydrocarbons from said second reaction zone in vapor phase into said 65 separating zone along with the hydrocarbons from said primary conversion zone whereby lower boiling hydrocarbons produced in both conversion zones are continuously removed from the system while unconverted hydrocarbons in vapor 70 phase are continuously recycled in said second conversion zone to any desired degree of exhaustion of the original charge to the system.
